Primary Examiner—Celia A Murphy(74) *Attorney, Agent, or Firm*—Porter, Wright, Morris & Arthur, LLP(57) **CLAIM**

The ornamental design for a shoe sole, as shown and described.

DESCRIPTION

FIG. 1 is a perspective view of a shoe sole according to my new design;

FIG. 2 is a bottom plan view thereof;

FIG. 3 is a right side view thereof;

FIG. 4 is a left side view thereof;

FIG. 5 is a front view thereof;

FIG. 6 is a rear view thereof;

FIG. 7 is a bottom plan view of an alternative embodiment of the design shown in FIGS. 1–6; the appearance being identical to the first embodiment except for an indication of surface contrast and surface pattern. The particular surface pattern appearing on the lugs, cleats, and edges of FIGS. 7 through 9 are understood to extend across their circumscribed areas.

FIG. 8 is a right side view of the alternate embodiment; and, FIG. 9 is a left side view of the alternate embodiment.
